UNITED STATES PATENT OFFICE

BERT O. TILDEN, OF TRENTON, NEW JERSEY, ASSIGNOR TO B. O. T. MANUFACTURING COMPANY, OF TRENTON, NEW JERSEY, A CORPORATION OF NEW JERSEY

DESIGN FOR A WATER CLOSET FLUSH TANK

Application filed May 26, 1931. Serial No. 39,997. Term of patent 3½ years.

To all whom it may concern:

Be it known that I, BERT O. TILDEN, a citizen of the United States, residing at Trenton, in the county of Mercer and State of New Jersey, have invented a new, original, and ornamental Design for a Water Closet Flush Tank, of which the following is a specification, reference being had to the accompanying drawing, forming a part thereof.

Figure 1 is a front elevation of the article,

showing my new design; Fig. 2 is a top plan; Fig. 3 is a side elevation; and Fig. 4 is a perspective view of the cover detached from the tank.

The dominant feature of the invention resides in the cover.

I claim:

The ornamental design for a water closet flush tank, as shown.

BERT O. TILDEN.
